UNITED STATES PATENT OFFICE.

GEORGE A. SCHOBERT OF RACINE, WISCONSIN, ASSIGNOR TO HARTMANN TRUNK COMPANY, OF RACINE, WISCONSIN, A CORPORATION OF WISCONSIN.

TRUNK-LOCKING DEVICE.

Application filed March 10, 1924. Serial No. 698,156.

This invention relates to improvements in trunk locking devices, more particularly adapted for locking the sections of a wardrobe trunk together.

It is one of the objects of the present invention to provide a trunk locking device which is adapted to automatically unlock or lock the lower portions of the trunk sections when the hasp member locking the top cover to the trunk sections is moved to open or locked position.

A further object of the invention is to provide a trunk locking device which will draw the trunk sections closely together during the locking operation.

A further object of the invention is to provide a trunk locking device in which a turning movement of the hasp member locking the upper portions of the trunk together will positively lock or unlock the lower sections of the trunk.

A further object of the invention is to provide a trunk locking device which is of simple construction, is strong and durable and is well adapted for the purpose described.

With the above and other objects in view, the invention consists of the improved trunk locking device and its parts and combinations as set forth in the claims, and all equivalents thereof.

In the accompanying drawings in which the same reference characters indicate the same parts in all of the views:

Fig. 1 is a front view of a trunk provided with the improved locking device, the trunk sections being shown in open position;

Fig. 2 is a detail view on a larger scale, of portions of the inner side of the trunk sections, showing the locking device mounted thereon, the parts being shown in partly open position;

Fig. 3 is a vertical sectional detail view taken on line 3—3 of Fig. 2;

Fig. 4 is a detail view of the inner side of the lower portions of the trunk sections showing the sections in locked position;

Fig. 5 is a horizontal sectional detail view of the hasp locked;

Fig. 6 is a detail view of the inner side of the trunk sections showing a slightly modified form of locking device mounted thereon;

Fig. 7 is a horizontal sectional view of the upper portion of the trunk taken on line 7—7 of Fig. 6; and

Fig. 8 is a sectional detail view taken on line 8—8 of Fig. 6.

Referring to the drawings, the numeral 10 indicates the drawer section, 11 the wardrobe section and 12 the top cover which is hinged to the open top of the wardrobe section for closing said top. The two sections are hinged together and adapted to be swung horizontally to open position after the top cover has been swung upwardly to open position.

The two sections are locked together by the improved trunk locking device 13 while the top cover of the wardrobe section is locked in closed position by a keyed hasp lock 14 which forms part of the device 13. The improved device comprises a fixed bracket 15 having an inwardly offset and upwardly extending keeper portion 16 provided with an angular clamping edge 17, a locking edge 18 and a stop shoulder 19. The bracket 15 is mounted on the inner side of the drawer section, near the bottom portion of the section and close to the open edge of the trunk. A locking bar 20 positioned on the inner side of the wardrobe section adjacent the open edge of the section is slidably mounted in guide members 21 and 22 secured to the inner side of the wardrobe section.

Said bar 20 carries a transverse extension or locking member 23 provided with a locking pin 24 which engages the angular or diagonally extending edge 17 of the keeper portion 16 and draws the two trunk sections together when the bar 20 is moved downwardly. When the trunk sections have been drawn firmly together, a further downward movement of the locking bar will cause the pin to engage the straight or locking edge portion 18 of the keeper to hold the parts in locked position. The shoulder 19 will limit the downward movement of the said pin 24.

The upper end portion of the locking bar 20 is provided with a line of perforations 25 which form in substance teeth 26 between said perforations and said teeth are engaged by the teeth of the segmental gear member 27 mounted on the hasp lock member 14. The wardrobe section of the trunk and the guide member 21 are slotted, as indicated by the numeral 28, to permit the teeth of the segmental gear member 27 to extend therethrough and enter the perforations of the bar, as shown in Fig. 3. The cover 12 is provided with a socket member 28' to receive 110

105 the teeth of the segmental gear member 27 to extend therethrough and enter the perforations of the bar, as shown in Fig. 3. The cover 12 is provided with a socket member 28' to receive 110

the lock portion 14' of the hasp lock 14 in locking the top cover in closed position. A transversely extending locking clip 29 is mounted on the hasp member 14 and is provided with an angularly extending locking portion 29' which enters the slot 30 of an escutcheon plate 31 mounted on the outer side of the drawer section so that when the hasp lock is in closed position the upper portion of the drawer section will be drawn toward the other section by the angular portion 29' and locked. The lower end of the bar 20 is bent outwardly as indicated by the numeral 20' to limit the upward movement of the said bar.

In the modified form shown in Figs. 6, 7 and 8, the hasp lock 32 is mounted on a short shaft 33 which extends through the wardrobe section 10 and is provided with an arm 34 at its inner end rigidly connected thereto. The outer end of the arm is pivotally connected to the reciprocal bar 20 and the lower end of the bar carries a locking hook plate or member 34 which is provided with a diagonally extending slot 35 terminating at its opposite ends in vertically extending holding portions 35'. A bolt 36 secured to the wardrobe section extends through the slot so that when the rod is pulled upwardly it will freely disengage the pin 37 of the keeper bracket 38 and unlock the trunk sections, and when the bar 20 is pushed downwardly, the hook portion 34' will engage the pin 37 and draw the two trunk sections together in moving diagonally to locked position. An angle bar 39 mounted on the wardrobe section is provided with a vertically extending elongated slot 40 through which the hook portion 34' extends and is guided.

The hasp lock 32 swings edgewise upwardly from a horizontal position to unlock the hook member from the keeper bracket, and is swung downwardly to lock the same. In the form of trunk in which this modified locking device is used, the hasp lock is mounted on the wardrobe section and the escutcheon socket plate 41 is mounted on the drawer section as shown in Fig. 7. When thus locked the top cover may be locked in any manner desired.

From the foregoing description it will be seen that the movement of the upper hasp lock to open or closed position positively unlocks or locks the lower lock of the trunk sections in a very simple manner.

What I claim as my invention is:

1. The combination with a trunk having two hinged together sections, of a means for locking the two sections together, comprising a keyed outwardly swinging locking member on one of the sections for locking the upper portions of the sections together, a locking means, including a fixed diagonally extending portion for positively draw-

ing and locking the lower portions of the two sections together, and a reciprocal bar connected to the keyed locking member and movable in a straight line for positively actuating the lower locking means when said upper locking member is moved outwardly to open or inwardly to closed position.

2. The combination with a trunk having two hinged together sections, of a means for locking the two sections together, comprising a keyed outwardly swinging locking member on one of the sections for locking the upper portions of the sections together, a bar connected to the keyed locking member and reciprocated thereby when the locking member is moved outwardly to open or inwardly to closed position, a locking member for the lower portion of one of the trunk sections which is connected to and positively actuated by the reciprocal bar, and a fixed locking member mounted on the lower portion of the other trunk section which is engaged by the other lower locking member to draw and lock the two sections together, one of said lower locking members having a diagonally extending portion which coacts with the other member to draw the sections together.

3. The combination with a trunk having two hinged together sections one of which is formed with an upper open end closed by a top cover, of a means for locking the three parts together, comprising a keyed outwardly swinging locking member on one of the sections for directly engaging and locking the top cover thereto and the upper portions of the sections together, a bar connected to the keyed locking member and reciprocated thereby when the locking member is swung outwardly to open or inwardly to closed position, a reciprocal locking member for the lower portion of one of the trunk sections which is connected to and positively actuated by the reciprocal bar, and a fixed locking member mounted on the other trunk section and engaged by the other lower reciprocal locking member to draw and lock the sections together, one of said locking members having an angular edge portion which coacts with the other reciprocal locking member to draw the two sections together.

4. The combination with a trunk having two hinged together sections, one of which is formed with an upper open end closed by a top cover, of a means for locking the two sections and the top cover together, comprising a keyed hasp lock hinged to one of the sections and movable outwardly and downwardly to open position, said hasp lock directly and lockingly engaging the top cover and the upper portion of the other trunk section and having segmental teeth extending radially into the trunk section with relation to the axis of the hinge, a vertically reciprocal bar positioned in the trunk

section provided with the hasp lock and having perforations which are entered by the segmental teeth to positively raise or lower the bar, the lower end portion of said bar 5 having a rigidly connected locking extension which projects into the other trunk section and is provided with a transverse pin, and a fixed locking plate mounted in the lower portion of said other section and hav-

ing a laterally offset and upwardly extending portion which is provided with an angular edge and a straight edge portion both of which are engaged by the transverse pin to draw the two sections together and lock the same when the sections are swung together. 10 15

In testimony whereof, I affix my signature.

GEORGE A. SCHOBERT.
